UNITED STATES PATENT OFFICE.

RICHARD REMING, OF NORWALK, OHIO, ASSIGNOR TO THE NORWALK VAULT COMPANY, OF NORWALK, OHIO, A CORPORATION OF OHIO.

MOLD FOR BURIAL VAULTS.

Application filed March 7, 1922. Serial No. 541,726.

To all whom it may concern:

Be it known that I, RICHARD REMING, a citizen of the United States, residing at Newton Street, Norwalk, in the county of 5 Huron and State of Ohio, have invented certain new and useful Improvements in Molds for Burial Vaults, of which the following is a specification.

My invention relates to a mold for a burial 10 vault or the like, and the novelty consists in the adaptation and arrangement of the parts as will be more fully hereinafter pointed out.

In the making of burial vaults or similar 15 containers, which are usually made of concrete, it has been found necessary to make so many different sizes in order to accommodate the many different sizes of coffins to be placed therein, that it has always been 20 necessary to make the molds so that they can be readily changed in size without too many parts and the attendant expense. My mold not only provides for a wide variety of changes in size, but also enables the operator 25 to make such changes easily and quickly. Also the heavy corner castings heretofore necessary in such molds have been eliminated by my device, thereby doing away with about one third of the weight and thus effecting a material saving in the labor involved in using the same.

Heretofore it has been necessary in making the cover of these vaults to trowel the cement or concrete over the base form which 35 is in the mold, which has been slow and expensive. My new cover mold provides a means of pouring the cement or concrete so that the cover can be made by the use of my mold in a small fraction of the time 40 heretofore required, thereby effecting a very large saving in the cost of the manufacture of the cover.

Referring to the drawings Figure 1 is a front elevation of the molds filled with the 45 plastic material, and with a portion cut away in vertical section to show the interior construction on the line 1-1 of Fig. 2; Figure 2 is a top plan view of the molds showing one end cut away transversely on 50 the line 2-2 of Figure 1 in order to show the interior construction; Figure 3 is a top plan view of the cover mold; Figure 4 is an end view of Fig. 3; Figure 5 is a vertical section on the line 5-5 of Fig. 3.

55 In the drawings 10 is a base member on

which are rigidly mounted retaining blocks 11 adapted to hold the outer mold in a fixed inverted position. The outer mold is composed of two side members 12, at each end of which is rigidly secured at 28 connecting 60 plates 13 which are adapted to be secured to the U-shaped end members 14 by means of threaded bolts 15. The lower edges of the side members 12 and the U-shaped ends 14 flare out at 16 so as to form a flare lip 17 65 on the upper edge of the vault when completed.

An inner mold member has side members 18, to which are rigidly secured at 19 connecting plates 20 at each end of 18 which 70 are adapted to connect said side members 18 to U-shaped end members 21 by means of threaded bolts 22. The side members 18 have support members 23 rigidly secured thereto at 24, and a cover 25 is adapted to 75 fit into the ends 21 and sides 18 and rest on the support members 23 and the connecting plates 20 at each end, so that said cover 25 effects a complete closure of the top of the inner mold, and the top surface of 25 is 80 level with the upper edges of side members 18 and 21. The lower outer edge of the side members 18 and end members 21 terminate in a flange 26, and a semicircular molding 27 is rigidly secured to 26 for the greater 85 part of its length on both the sides 18 and the ends 21.

The cover mold has a base member 29, end members 30 which are detachably secured at 31 to the base member 29, side members 32 90 which are secured in a fixed position against the base member 29 and end members 30 by means of extension members 33 which are bolted together by means of bolts 34 and nuts 35 running through each pair of extensions 33 at each end of the cover mold. The cover mold has a top plate 36 which is rigidly secured to the side members 32 at 37, and a longitudinal slot 38 runs the entire length of top plate 36. The top plate 36 100 also has four openings 39 into which suitable handles 40 are adapted to be mounted when the plastic concrete or cement is poured into the slot 38 so that they will imbed therein. A semi-circular molding 41 is rigidly secured to the ends 30 and the side members 32 for the greater part of their length near the lower inside edge of the same. When the concrete is poured into the slot 38 it is apparent that the concrete will gradually fill 105 110

the open space above the base 29, so that the pouring of the concrete in the slot 38 until the said space is filled, will effect the completion of the cover 44 without any troweling. When the cover 44 has set, the side members 32 can be readily removed by removing the nuts 35 from the bolts 34, and the ends 30 can then be readily removed by the removal of the fastening means 31, whereupon the completed cover 44 can be lifted off the base member 29.

As the molds are in the proper position for use, as shown in Figures 1 and 2, some plastic material, such as concrete, can be poured into the space between the inner and outer molds, with the reinforcing metal wire 49 already in place. When the plastic material has set properly the outer end members 14 may be removed by the removal of the threaded bolts 15, thereby permitting the side members 12 to also be removed. The body 42 of the vault can then be turned over so that the inner mold member may be removed.

If it is then desired to make a larger vault body the side plates 12 can be secured to U-shaped end members 14 of a wider and slightly longer dimension. The cover 25 of the inner mold member having been first removed the side members 18 of the inner mold may be separated from the U-shaped end members 21 by removing the threaded bolts 22, and wider and longer U-shaped members 21 may be then secured to the side members 18 of proper proportion to the new end members 14. A new cover 25 can then be placed in position as before described, and the body mold will then be set up ready to mold a larger body 42 in the same way as previously described. It is apparent that as many sizes of U-shaped

end members 21 and 14 may be provided as is desired for making the sizes of bodies 42 required, and different size covers 25 must also be provided to go therewith.

I claim:

1. In a cover mold for a container the combination of a base member, end and side members separably secured thereto and a cover adapted to be secured to said side members having a longitudinal slot near the middle thereof, and holes adapted to receive four handles at suitable intervals in said cover.

2. In a cover mold for a container the combination of a base member, end and side members separably secured thereto and a cover adapted to be secured to said side members having a longitudinal slot near the middle thereof, and holes adapted to receive four handles at suitable intervals in said cover, said side and end members having a semi-circular moulding for most of their length near the lower edge of the inside thereof.

3. In a cover mold for a container the combination of a base member, end and side members separably secured thereto and a cover adapted to be secured to said side members having a longitudinal slot near the middle thereof, and holes adapted to receive four handles at suitable intervals in said cover, said side and end members having a moulding for most of their length near the lower edge of the inside thereof.

In testimony whereof I affix my signature in presence of two witnesses.

RICHARD REMING.

Witnesses:

JOHN H. COX,
R. H. LENZ.
